UNITED STATES PATENT OFFICE.

CLAUDIUS GRATALOUP AND JEAN B. LEYMARIE, OF PARIS, FRANCE.

UMBRELLA-SLIDE.

SPECIFICATION forming part of Letters Patent No. 261,151, dated July 18, 1882.

Application filed April 20, 1882. (No model.) Patented in France October 15, 1881, No. 145,358.

To all whom it may concern:

Be it known that we, CLAUDIOUS GRATALOUP and JEAN BAPTISTE LEYMARIE, citizens of France, residing in the city of Paris, have invented a new and useful Improvement 5 in Umbrella-Slides, (for which we have obtained a patent in France for fifteen years, dated October 15, 1881, No. 145,358,) of which the following is a specification.

This invention relates to that part of the mounting of an umbrella, sunshade, or parasol which secures the ends of the stretchers or braces when the umbrella is opened.

The object of the invention is to supersede 15 the ordinary tubular slotted runner and spring-catches.

The invention consists of a tubular runner with an upper overhanging notched cap, on which runner, and beneath which cap, is another runner carrying the stretchers. These 20 two tubes or runners slide one on the other, so that free play is given to the stretchers in either opening or closing the umbrella.

In the accompanying drawings the principle 25 of the invention is shown; but the form and materials of construction of the parts may be varied.

Figure 1 is a side view of the improved slide, the umbrella being closed and the stretchers *f* shown. Fig. 2 is a longitudinal section of the 30 parts forming the invention, the umbrella being partly open and showing one of the stretchers in the position it would occupy. Figs. 3 to 7 are details of the several parts. Fig. 8 is 35 longitudinal section of the parts, taken at right angles to Fig. 2.

a is the stick of the umbrella. *b* is a tubular runner fitting the stick. To the upper part of the runner *b* is soldered or otherwise fixed 40 an overhanging cap, *c*, which is pierced with the same number of apertures as there are stretchers or braces *f*. At the lower end the tube *b* is screw-threaded to receive the annular flange *e*. Around the tube *b* is placed, beneath the cap *c*, but above handle-ring *e*, a 45 second tube or slide, *g*, which has a lower han-

dle-ring, *h*, and at the upper end a crown-ring, *k*, in which crown-ring the inner ends of the stretchers *f* are pivoted in the ordinary manner. The crown-ring *k* is covered and concealed by the cap *c*.

After closing the umbrella in the usual manner all that is required to lock it is to hold the slide *g* by the finger and thumb at the handle part *h* and push with the handle-ring *e* of the 50 slide *b* upward, thereby raising the cap *c* and carrying its solid part around the pivoted inner ends of the stretchers *f*. In this position the parts will be maintained and the stretchers held close to the handle by the frictional 55 contact between the tubes *b* and *g*. In opening the umbrella the inverse motion is effected—that is to say, before the runners are lifted the slide *b* is drawn down and the slide *g* held fast until the cap *c* presents its apertures in 60 line with the pivoted ends of the stretchers. Then by pushing on the ring *h* the runners are lifted, and the umbrella is opened and remains 65 open as long as desired.

It might happen that in opening the umbrella the ring *e* of the slide *b* is raised by accident, to prevent which a spring, *r*, is lodged in the slide *b* and abuts against the ring *h*. Fig. 8, when the umbrella is prepared for opening. In closing, it suffices to press the spring 70 *r* inward into a suitable recess furnished in the slide *b*.

We claim—

1. The combination of the runner-tube *b*, having slotted cap *c*, with the embracing-tube 80 *g*, having crown-ring *k*, and with the stretchers or braces *f*, substantially as herein shown and described.

2. The tube *g* and crown-ring *k*, combined with the tube *b*, slotted cap *c*, spring *r*, stick 85 *a*, and stretchers *f*, substantially as herein shown and described.
